America, a corporation of Delaware

Application July 28, 1930, Serial No. 471,214
In the Netherlands July 27, 1929

4 Claims. (Cl. 177—314)

This invention relates to an alarm device for safeguarding rooms and other spaces and is based on the discovery that the reception-intensity of an ultra-short wave receiver is greatly influenced by variations occurring in the vicinity of a transmitter and a receiver. The "vicinity of the transmitter and the receiver" is to be understood hereinafter to mean the surroundings of about ten wave lengths.

On the transmitter and the receiver being arranged in a room or other space, a definite oscillatory condition arises, said condition being controlled by the surroundings of the transmitter and the receiver.

If in such a space a variation in condition occurs, for example if any one enters the room, the prevailing oscillatory condition will become varied, and the reception intensity is thus at once affected. This phenomenon is not limited by a closed chamber but also occurs in the open as long as there is in the vicinity of the transmitter or receiver some object that can serve as a reflector.

Thus, for example, a bush or shrubbery may suffice to bring about a considerable variation in the reception-intensity.

It has been found that when the hand is approached to a short-wave transmitter or receiver, the tuning and consequently also the reception-intensity varies. This principle can be applied to alarm signals and the variation in the reception-intensity can be rendered perceptible in a suitable manner at a distant point. However, these capacitative influences only occur when the variation takes place in the immediate vicinity of the transmitter or receiver.

The alarm device according to the invention is based on another phenomenon which has the great advantage of not being dependent upon a small spacing between the transmitter or receiver and the object or body that induces the variation in the tuning.

It may be imagined that in an enclosure containing the transmitter stationary waves are produced by reason of reflection on the walls, the floor and the ceiling, the distribution and the arrangement of the nodes and loops of said waves being influenced inter alia by the objects enclosed within the room. If anyone enters the enclosure, the conditions controlling the distribution of the field become varied and the result will be that quite a different field distribution is established.

The body of the person that enters may in some measure be looked upon as a secondary trans-

mitter which transmits part of energy retained and thus alters the field distribution.

Evidently, the larger—the size of the extraneous body and of the room in relation to the wave length, the greater is the variation in the field distribution. It has thus been found that an essential condition of securing a powerful influence on the reception-intensity consists in that the size of the room in which the transmitter and the receiver are arranged should be large in relation to the wave length. The invention will be more clearly understood by reference to the accompanying drawing in which a diagrammatic survey is given of the arrangement of the component members of an alarm device according to the invention.

Referring to the figure, 1 designates a transmitter, 2 a receiver and 3 an alarm signal which becomes operative when variations occur within the room in which the transmitter and receiver are arranged.

The transmitter and receiver are preferably furnished with a triode to which a Lecher system is connected. The arrangement of the transmitter and the receiver per se is no important feature of the invention but it is essential that they should be arranged for very short waves, say of the order of a meter.

For suitable receiving and transmitting apparatus for accomplishing the purposes of this invention attention is invited to the article in the Proc. I. R. E., June 1928, page 715 by Yagi, entitled "Beam transmission of ultra-short waves."

The output circuit of the receiver is connected to a conductor 4 which leads to the alarm device 3 proper. The receiver includes a detector which converts high frequency oscillations into direct current or into low frequency oscillations which can be transmitted through the conductor 4 to a distant point. If for the supply of the plate of the transmitter an alternating current is used a wave modulated in amplitude is emitted which after rectification by the receiver supplies an alternating current which can be easily transmitted to the alarm device.

The alarm device may be made in different ways. The construction of the alarm device per se does not fall within the scope of the invention. It may, for example, consist of an alternating current relay the armature of which as soon as it drops by reason of the variation in current strength in the relay winding closes a circuit of an acoustic or optical signal. As an alternative, it is, of course, possible to operate entirely with

direct current. Preference is given to a closed circuit relay. If necessary, the currents received may be amplified subsequent or prior to detection.

5. Preferably, the receiver is arranged at a point where the reception-intensity is maximum.

I claim:

1. In an alarm device for indicating the presence of an extraneous body within an enclosure, 10 a source of radiant energy within the enclosure for permeating the enclosure with energy having a wave length which is small compared to the size of the enclosure, a radiant energy intercepting device in the enclosure positioned therein so as to 15 be affected by energy impinging thereon directly from the source as well as indirectly as from energy from the source as reflected from the walls of the enclosure and objects therein and indicating means associated with the intercepting device for indicating changes in the intensity of the energy received by the intercepting device as caused by the presence of an extraneous body within the enclosure.

2. In an alarm system the steps in a method 25 of producing indications of the presence of extraneous bodies within an enclosure which comprise permeating the space within the enclosure with radiant energy waves having a wave length which is small compared with the dimensions of 30 the enclosure, normally producing from the radiant energy within the enclosure responses of predetermined intensity characteristics dependent upon the interception of the radiant energy at a point within the enclosure, both directly from 35 the source and from reflections of the energy from the walls of the enclosure and objects there-

in and causing a perceptible change in the intensity response characteristics by the reflection and absorption characteristics of any extraneous body present within the enclosure to thereby indicate immediately the presence of the extraneous body 5 therein.

3. The method of detecting the introduction of a new object into a given substantially enclosed space and the disturbance of objects therein, which consists in propagating in said space continuous waves of a wavelength substantially greater than that of light, which waves are reflected by the confines of said space and by objects therein to produce reflected waves, and which reflected waves form with each other and 15 with said propagated waves a wave pattern substantially filling said space; in receiving the waves comprised in said pattern at a fixed region within said space; and in signalling variations in the amplitude of said received waves, whereby to detect changes in said pattern.

4. The method of detecting the introduction of an object into a given substantially enclosed space and the disturbances of objects therein, which method includes the steps of propagating 25 in said space continuous energy waves, which waves are reflected by the confines of said space and by objects therein to produce reflected waves, and which reflected waves form with each other and with the propagated waves a pattern sub- 30 stantially filling the space; receiving the waves comprised in said pattern at a fixed region within said space; and signalling variations in amplitude of the received waves whereby to detect changes in said pattern.

MAXIMILIAAN JULIUS OTTO STRUTT.
